CLAIM

The ornamental design for a bag, as shown and described.

DESCRIPTION

The file of this patent contains at least one photograph executed in color. Copies of this patent with color photographs(s) will be provided by the Office upon request and payment of the necessary fee.

FIG. 1 is a photographic top, front, left perspective view of a bag showing our new design;

FIG. 2 is a photographic left side view thereof;

FIG. 3 is a photographic right side view thereof;

FIG. 4 is a photographic top, rear perspective view thereof; and,

FIG. 5 is a photographic rear perspective view thereof.

The broken lines represent unclaimed portions of the bag that form no part of the claimed design.
